GARMENT OR ATTACHMENT FOR CONTROLLING THE DISTRIBUTION, PRESSURE, AND CIRCULATION OF BODY FLUIDS

David M. Clark, Worcester, Mass., and Earl H. Wood, Rochester, Minn.; said Wood assignor to said Clark

Application September 14, 1946, Serial No. 697,118

7 Claims. (Cl. 128—1)

1

The present invention relates to an improved garment, or attachment for controlling the distribution, pressure and circulation of body fluids and thereby enable the occupant of an aircraft to withstand the abnormal forces to which his body is subjected as a result of rapid and extreme changes in the aircraft's speed and direction of flight.

Experience has shown that maneuvers of fast and high powered aircraft create forces which are frequently great enough to render the occupants temporarily blind and sometimes unconscious. These forces act upon the body fluids, particularly blood, and the tissues of the body so that when a fast airplane is banked and turned, or dived and then leveled off, these body fluids are driven down, away from the head. The resulting reduction or stoppage of blood circulation to the head, if of sufficient magnitude and duration causes a dimming or complete loss of vision, known as "blackout," and if the force is great enough and is sustained long enough, complete unconsciousness may result.

Since the forces discussed above increase in proportion to the square of the velocity of the airplane and in inverse proportion to the radius of the turn, the maneuvering of fast airplanes is definitely limited by the ability of the pilot and other occupants to withstand the forces that cause the above described severe physiological changes within the body. The object of the present invention is to provide an improved garment or attachment, for occupants of fast airplanes which will so control the distribution and pressure of body fluids as to enable the wearer to successfully withstand abnormal forces created by rapid and extreme changes in the speed and direction of the aircraft's flight. This garment is particularly characterized by the completeness of the protection afforded the wearer and its simplicity and lightness permits the wearer to sit normally, unencumbered by heavy parts that would interfere with his necessary movements.

Briefly stated, the device of the present invention consists of a garment, or an attachment, having incorporated therein a bladder, or series of bladders, which are adapted to be inflated automatically so as to progressively apply pressure on the thighs, the abdomen and, if desired, the legs and arms of the wearer. The inflated bladders are adapted to conform closely to the associated body areas, and restrict the flow of body fluids to the dependent portions of the body when the wearer of the garment is subjected to the abnormal forces discussed above, resulting

2

from the rapid and extreme changes in an aircraft's speed and the direction of flight.

Because of the location of the bladders at critical points in the vascular system of the body, the garment is also adapted for extremely high altitude flying, so as to pressurize the body and provide considerable protection to the wearer from the disturbing physiological effects of extremely high altitudes. The garment may also be employed for medical treatments and other and further objects and advantages of our invention will be made apparent by the following detailed description thereof taken in connection with the accompanying drawings, in which

15 Fig. 1 is a view in front elevation of the outside appearance of a protective garment in the form of a coverall suit embodying the present invention.

20 Fig. 2 illustrates diagrammatically the bladder system employed in the suit of Fig. 1.

Fig. 3 is a fragmentary view illustrating the manner of joining the bladders over the abdominal area, showing the suit partially open, in preparation for donning the same.

25 Fig. 4 is a horizontal, sectional view along the line 4—4 of Fig. 3, with the suit closed.

Fig. 5 is a view similar to Fig. 1 illustrating a modified form of suit with certain bladders outside the garment.

30 Fig. 6 diagrammatically illustrates bladder system employed with the suit of Fig. 5.

Fig. 7 is a detailed view showing the application of bladders to the outside of the legs with an arrangement for distributing the bladder pressure around the legs.

Fig. 8 is a perspective view of one leg bladder attachment, as seen from the rear.

Fig. 9 is a sectional along the line 9—9 of Fig. 7.

40 Fig. 10 illustrates the application of the pressure distributing arrangement with reference to the bladder of an upper arm area.

Fig. 11 illustrates application of the pressure distributing arrangement to the abdominal area.

Like reference characters refer to like parts in the different figures.

Referring first to Figs. 1 and 2, the invention is shown, for purposes of illustration, as being embodied in a garment made as a complete coverall suit 1, having certain areas thereof lined with bladders located so as to apply pressure to the calves and thighs and over the abdominal area of the wearer. The arrangement of these bladders is shown diagrammatically in Fig. 2 with the bladders being indicated generally in dotted lines in Fig. 1.

The lowermost bladders 2 are positioned in the vicinity of the calves of the wearer, the intermediate bladders 3 are positioned in the vicinity of the thighs of the wearer, and the uppermost bladders 4 are positioned over the abdominal area, as will be apparent from the dotted line showing of Fig. 1. The several groups of bladders on each side of the suit 1 are connected in series with each other by tubes 5 so that air, or any other fluid pressure medium for inflating the bladders, will enter the right-hand and left-hand groups of bladders progressively, this progressive inflation being an important feature of the present invention. For this purpose, the lowermost bladder 2 of each group of calf bladders is connected by a tube 6 to a common supply tube 7, which leads from a special valve 8 that is adapted to automatically control the admission of the pressure medium to the supply tube 7 from a suitable pressure source indicated diagrammatically at 9 as a tank or pump. The tubes 6 lead off from the supply tube 7, with one tube 6 passing around the neck of the suit and then downwardly parallel to the other tube.

The top of the middlemost bladder 4 of one group of abdominal bladders is connected by a tube 10, passing up and around the back of the neck of the suit 1 to join a short tube 11 from the innermost bladder 4 of the other group of abdominal bladders. These two tubes 10 and 11 are connected in common to a tube 12 leading back to the control valve 8 which is adapted to regulate the amount of pressure in proportion to the centrifugal or other abnormal force to which the wearer of the suit 1 is being subjected as a result of the sudden and extreme changes in the speed and direction of flight of the airplane.

The specific construction of the control valve 8 forms no part of the present invention, and it is sufficient for an understanding thereof to state that the valve 8 is operated automatically by a weight 8a to control the passage of pressure from the source 9 through the tubes 7 and 12 in response to the creation of abnormal forces during the flight of the airplane. For purposes of illustration, the valve 8 is indicated as being of the type disclosed in the pending application of David M. Clark, and Henry W. Wilder filed July 12, 1946, Serial No. 683,098, for a protective system for aircraft occupants.

Whenever the valve 8 functions automatically in response to forces developed during the flight of the airplane, the air from the pressure source 9 is admitted to the supply tube 7 from which it passes through the tubes 6 to simultaneously enter the lowermost bladder 2 of each group of calf bladders. The air continues upwardly through all the bladders 2 and the tubes 5 to enter the lowermost bladders 3 of the thigh bladders, and then passes upwardly from these bladders to simultaneously enter the outermost bladder 4 of each group of abdominal bladders. The air under pressure then progresses across the bladders 4 towards the middle of the abdomen to complete the progressive inflation of all the bladders 2, 3 and 4 of the system. The net result of the above described functioning of the bladder system is that the air supply enters at, or near, the ankles of the wearer, and then progresses generally upward in the vicinity of the thighs before reaching the uppermost abdominal bladder 4, so that the wearer of the suit is subjected to a pressure wave effect starting at the ankles and ending in the abdominal area. As a result, the wearer

of the suit is enabled to withstand the most disturbing of the abnormal forces developed during flight of the airplane without dimming of vision, or loss of consciousness.

5 By reason of the inter-connection of the several groups of bladders 2, 3 and 4 in series, with the same relation on each side of the wearer's body, the pressure wave described above is applied uniformly on each side so that there is no possibility of any unbalancing effect which might result from an unsymmetrical disposition of the pressurized areas with relation to the central axis of the wearer's body. After all of the bladders have become inflated through the tube 7 to the 15 desired degree, as a result of the functioning of the valve 8, excess air, over physiological requirements for the conditions encountered, is permitted to escape through the tubes 10, 11 and 12, with the amount of escaping air being adjusted by the 20 valve 8 to maintain the necessary pressure in the entire bladder system.

As previously pointed out, the abdominal bladders 4 are connected in two separate groups on each side of the body with the pressure working 25 inwardly from the outermost bladders to the return tubes 10 and 11. This group arrangement of the abdominal bladders facilitates donning of the suit by the use of a centrally located fastener device 13 in the front of the suit as shown in 30 Fig. 1. In view of the importance of effectively maintaining a pressurized area over the center of the abdomen, the suit provides a special construction of the central area which prevents separation of the bladders and will insure close engagement between the innermost bladders 4 of 35 each abdominal group, so that full pressure will always be maintained over the center of the abdomen after the suit has been donned.

As best shown in Figs. 3 and 4, each group of 40 abdominal bladders 4 is confined in a pocket 14 constituted in part by the front of the suit 1 and a rear wall 15. The rear wall 15 of each pocket 14 extends substantially to the edge of the front fastener device 13 and it is connected to the front 45 of the suit above and below the bladders 4 by stitching 15a. The edge of the wall 15 between its points of connection to the front of the suit is free and a panel 16 is interposed between the rear wall 15 and the front of the suit to constitute an expandible end for each pocket 14.

In order to provide for bringing the bladder pockets 14 together with their end panels 16 face to face, each rear wall 15 provides a flap 17 with the abutting edges of the flap 17 provided with 55 the cooperating parts of a slide fastener device 18. The fastener device 18 is shown closed in Fig. 3 with the front central fastener open to show the fullness of the end panels 16 of each bladder pocket 14, the bladders 4 then being deflated.

60 When donning of the suit has been completed by fully closing the front fastener device 13, as shown in Fig. 1, the end panels 16 are disposed in abutting relation. Therefore, by reason of the fullness of these panels 16, subsequent inflation 65 of the abdominal bladders 4 will cause the innermost bladders of each group to closely engage each other, as illustrated in Fig. 4. As a result, full pressure is maintained in the center of the abdominal area which would not be possible were 70 the abutting edges of the bladders to be confined in tight pockets on either side of the fastener device 13.

Referring now to Fig. 5, there is shown a modified form of garment wherein certain of the bladders are disposed outside the garment in co-

operation with an arrangement whereby the inflated bladders are caused to conform closely to the limbs of the wearer, as well as to the abdominal area. This modified form of suit 19 is shown as a coverall in Fig. 5, and the arrangement of the bladders employed in connection with this suit is shown diagrammatically in Fig. 6. The bladder arrangement consists of thigh bladders 20 confined within a conforming sleeve 21 encircling each thigh portion, arm bladders 22 confined within a conforming sleeve 23 encircling each upper arm portion, and two groups of abdominal bladders 24 disposed inside the abdominal area of the suit 19 in association with a conforming belt 25. The uppermost thigh bladders are connected to the outermost abdominal bladders 24 by tubes 26 and branch tubes 26a lead off from tubes 26 to the arm bladders 22. The lowermost bladder 20 of each group of thigh bladders is connected by a tube 27 to a common supply tube 28 which leads from a valve 29 of the same general character as the valve 8 to automatically control the admission of a pressure medium to the tube 28 from a suitable pressure source.

When the valve 29 functions automatically in response to force developed during the flight of the airplane, air from the pressure source is admitted to the supply tube 28 from which it passes through the tubes 27 to simultaneously enter the lowermost bladder 20 of each group of thigh bladders. From these bladders, the air continues upwardly to the tubes 26 to finally enter the outermost bladder 24 of each group of abdominal bladders, as well as the separate arm bladders 22. Admission of the air to the bladders 22 and 24 completes the progressive inflation of the system and as shown the valve 29 maintains the pressure without the necessity of a return tube such as is shown in Fig. 2. The net result of the above described functioning of the bladder system is that the pressure medium enters in the vicinity of the thighs and then progresses upwardly to the arms and the abdominal area, with the pressure being so regulated as to be arterially occlusive during the period of exposure to the greatest forces.

As previously described, the thigh bladders 20 and the arm bladders 22 are associated with the sleeves 21 and 23 respectively so as to closely conform the inflated bladders to the leg or the arm of the wearer. The same bladder conforming action is also obtained in connection with the abdominal bladders 24 by means of the belt 25 encircling the waist of the suit 19 and these pressure distributing arrangements will next be described in detail with reference to Figs. 7 to 11, inclusive.

As best shown in the left-hand side of Fig. 7, the group of thigh bladders 20 is carried by the outside of the upper leg portion 39 of the suit 19 with the bladders extending lengthwise around the thigh portion and secured to the outside of the suit with their ends spaced apart on the underside of the thigh of the wearer. The sleeve 21 which encloses the bladders 20 is formed of separate flaps 31 shown turned back on the left-hand leg of Fig. 7 and closed over the bladders 20 on the right-hand leg by means of a slide fastener 32. The left-hand flap 31 is secured to the back of the leg portion of the suit by means of a series of straps 33 which extend underneath the thigh portion and are secured to the suit adjacent to the right-hand edge of the bladders 20. Similarly the right-hand flap 31 provides a series

of straps 33 alternately arranged with the left-hand straps and extending behind the thigh portion to a point where they are secured to the suit adjacent to the right-hand edge of the bladders 20.

The above described arrangement is shown in section in Fig. 9 and in perspective in Fig. 8 looking from the rear of the suit, with the bladders 20 indicated in dotted lines. From this showing it is apparent that the straps 33 are in crisscross relation behind the thigh of the wearer so that when the front fastener 32 is closed, the flaps 31 tend to conform the bladders 20 to the shape of the wearer's thigh. Normally, the straps are relatively loose when the bladders 20 are in a deflated condition as shown in Fig. 8.

However, when admission of air pressure to the bladders 20 inflates the same under conditions previously described, the front walls of the bladders 20 exert an outside pressure on the then closed flaps 31 of the sleeve 21, as shown in the transverse sectional view of Fig. 9, taken through the thigh of the wearer. This outward pressure on the flaps 31 is indicated by the small arrows in Fig. 9 and as the bladders 20 are fully inflated, this pressure results in each flap 31 exerting a pull in the direction of the large arrows in Fig. 9. These pulls are transmitted by the crossed straps 33 to opposite ends of the bladders 20 with the net result that the bladders are conformed to the wearer's thigh to distribute the pressure over the entire front thigh area and around the sides.

In order to permit adjustment of each sleeve 21 to the thighs of wearers of different build, one flap 31 of each pair provides a gusset 34 extending parallel to the fastener with the edges of the gusset adapted to be adjustably drawn together by a series of straps 35 and cooperating buckles 36. After a wearer has donned the suit 19, he is able to make the proper adjustment of the girth of the sleeve 21 through regulating the relative tightness or looseness of the gusset 34 by means of the straps 35 and buckles 36.

The above described arrangement for conforming the inflated thigh bladders 20 to the wearer is also applied to the arm bladders 22 through their associated sleeves 23. As shown in Fig. 10, each bladder 22 extends part way around the arm with a spacing between the points of attachment of its ends to the upper arm portion 37 of the suit. The associated sleeve 23 is shown as being made in one piece partially encircling the arm, with ends of the sleeve 23 connected to the arm portion 37 adjacent to opposite ends of the bladder 22 by means of crossed straps 38. Obviously, when the arm bladder 22 is fully inflated, the outward pressure exerted on the encircling sleeve 23 will result in opposed pulls on the ends of the bladder, with a resulting forming or molding of the bladder 22 around the upper arm of the wearer to assure a most effective application of the pressure. The sleeve 23 provides a gusset 39 and suitable straps 40 and buckles 41 for adjusting the girth of the sleeve.

As previously indicated, the bladders 24 for the abdominal area are secured inside the waist portion of the suit 19 with an arrangement for holding the innermost bladders of each group closely together in the center of the abdomen, as described in detail with reference to Fig. 3. In order to conform the inflated bladders 24 to the abdominal wall, the suit provides the previously mentioned belt 25 the construction of which is shown in the fragmentary, phantom view of Fig. 11, wherein the portions encircled by the belt 25 are shown in dotted lines.

The belt 25 comprises flaps 24 normally held closed by a slide fastener 43 in front of the suit. Each flap 42 extends around the waist of the suit and partially behind, and terminates in an enlargement 44, the edge of which is connected by straps 45 to the opposite side of the back of the suit. The straps 45 from each flap 42 are in crisscross relation so, that when the belt 25 is closed by the fastener 43, inflation of the bladders 24 against the flaps 42 will cause opposed pulls on the back of the suit to exert forces tending to conform the bladders 24 of each group closely to the outside of the abdominal area.

In order to increase the comfort of the wearer of the suit 19, there is provided an improved crotch construction shown in Fig. 7 consisting of outside leg gussets 46 and centrally located panels 47 extending below the waist of the suit and beneath the crotch. The fullness of these gussets 46 and panels 47 gives a freedom of action which insures the comfort of the wearer of the suit when in a sitting position, even with the thigh bladders 20 and the abdominal bladders 24 fully inflated.

From the foregoing, it is apparent that by the present invention there is provided an improved device for preventing an unnatural distribution of fluids within a human body which is subjected to abnormal forces set up when the body is accelerated in space, as when in an aircraft. Furthermore, by reason of the inherent capabilities of the device, our garment or attachment may also be effectively employed by hospitals, and clinics, for the treatment of patients who are suffering from various maladies affecting the human vascular system. When so employed for purely medical purposes, the garment is effective to either maintain a normal distribution of body fluids, or to actually increase a patient's blood pressure. It has been found that the massaging effect of the applied bladders particularly when used to obtain a pressure wave, produces very beneficial results on patients suffering from certain of the above noted maladies.

We claim:

1. A garment comprising, a body-encircling section, two independent leg-encircling sections attached to an depending from said body section, a plurality of bladders incorporated with and spaced longitudinally of each of said leg sections with each bladder disposed transversely of such section, a plurality of short tubes connecting the bladders of each leg section in a series relation, a bladder incorporated with said body section, a pair of tubes each connecting said last mentioned bladder with that bladder of a respective one of the leg section bladder groups which is nearest the body bladder, a pair of fluid-supply tubes each of which is connected to that bladder of a respective one of the leg section bladder groups which is farthest removed from said body bladder, and means to connect said two last mentioned tubes to a fluid supply source.

2. A garment comprising, a body-encircling section having a slit opening extending longitudinally thereof, fastening means carried upon said body section for closing said slit opening, a pair of bladder elements of which each is incorporated with said body section at a respective one of the sides of said slit opening, two independent leg-encircling sections attached to and depending from said body section, a plurality of bladders incorporated with and spaced longitudinally of each of said leg sections with each bladder disposed transversely of such section, a plurality of short tubes connecting the bladders of each leg section in a series relation, a pair of

tubes each connecting a respective one of said two body bladders with that bladder of a respective one of the leg section bladder groups which is nearest such body bladder, a pair of fluid-supply tubes of which each is connected to that bladder of a respective one of the leg section bladder groups which is farthest removed from said body bladders, and means to connect said two last mentioned tubes to a fluid supply source.

3. A garment comprising, a body-encircling section, two independent leg-encircling sections attached to and depending from said body section so as to define therebetween and at their juncture with said body section a crotch portion, said body section having a slit opening extending longitudinally thereof and toward said crotch portion, fastening means provided upon said body section for closing said slit opening, a pair of bladders each disposed adjacent a respective side of said slit opening and adjacent said crotch portion, pockets provided by said body section on each side of said slit opening for confining said bladders, with each pocket providing a free panel whose one edge portion is secured to said body section directly adjacent the slit opening, fastening means associated with the two opposite edge portions of said panels so as to cooperate with said first fastening means for bringing said panels in face-to-face engagement when both fastening means are closed, whereby said bladders, when inflated, are maintained in close engagement along the line of said slit opening, a bladder associated with each of said leg portions, and means for connecting all of said bladders with a fluid supply source.

4. A garment, comprising, an inner body-encircling sleeve, an inflatable bladder extending transversely about said inner sleeve so as partially to encircle the same, an outer sleeve extending transversely about said bladder and said inner sleeve so as partially to encircle the latter and being positioned so that the open end portions thereof substantially coincide with those of said bladder, a series of straps connecting each open end portion of said outer sleeve to said inner sleeve at a location adjacent the opposite open end portion of said outer sleeve to cause said outer sleeve to exert opposed pulls on said bladder and conform it to the contour of the body of the wearer in response to inflation of said bladder, and means for connecting said bladder to a source of fluid supply.

5. A garment comprising, a body-encircling section, two independent leg-encircling sections attached to and depending from said body section so as to define therebetween and at their juncture with said body section a crotch portion, said body section having a slit opening extending longitudinally thereof and toward said crotch portion, fastening means provided upon said body section for closing said slit opening, a pair of bladders each disposed adjacent a respective side of said slit opening and adjacent said crotch portion, pockets provided by said body section on each side of said slit opening for confining said bladders, with each pocket providing a free panel whose one edge portion is secured to said body section directly adjacent the slit opening, fastening means associated with the two opposite edge portions of said panels so as to cooperate with said first fastening means for bringing said panels in face-to-face engagement when both fastening means are closed, whereby said bladders, when inflated, are maintained in close engagement along the line of said slit opening, a plurality of bladders incorporated with and spaced longi-

tudinally of each of said leg sections with each bladder disposed transversely of said section, a plurality of short tubes connecting the bladders of each leg section in a series relation, a pair of tubes each connecting a respective one of said two body bladders with that bladder of a respective one of the leg section bladder groups which is nearest such body bladder, a pair of fluid-supply tubes of which each is connected to that bladder of a respective one of the leg section bladder groups which is farthest removed from said body bladders, and means to connect said last two mentioned tubes to a fluid supply source.

6. A garment comprising, a body-encircling section, two independent leg-encircling sections attached to and depending from said body section so as to define therebetween and at their juncture with said body section a crotch portion, said body section having a slit opening extending longitudinally thereof and toward said crotch portion, fastening means provided upon said body section for closing said slit opening, a pair of inflatable bladders each disposed adjacent a respective side of said slit opening and adjacent said crotch portion, an inflatable bladder extending transversely about each of said leg sections so as partially to encircle the same, an outer sleeve extending transversely about each of said leg bladders and its associated leg section so as partially to encircle the latter and being positioned so that the open end portions thereof substantially coincide with those of its associated bladder, a series of straps connecting each open end portion of a respective one of said leg sleeves to its associated leg section at a location adjacent the opposite open end portion of said sleeve to cause said sleeve to exert opposed pulls on said bladder and conform it to the contour of the leg of the wearer in response to inflation of said leg bladders, and means for connecting said bladders to a source of fluid supply.

7. A garment comprising, a body-encircling section, two independent leg-encircling sections attached to and depending from said body section so as to define therebetween and at their juncture with said body section a crotch portion, said body section having a slit opening extending longitudinally thereof and toward said crotch portion, fastening means provided upon said body section for closing said slit opening, a pair of bladders each disposed adjacent a respective side of said slit opening and adjacent said crotch portion, pockets provided by said body section on each side of said slit opening for confining said bladders, with each pocket providing a free panel whose one edge portion is secured to said body section directly adjacent the slit opening, and fastening means associated with the two opposite edge portions of said panels so as to cooperate with said first fastening means for bringing said panels in face-to-face engagement when both fastening means are closed, whereby said bladders, when inflated, are maintained in close engagement along the line of said slit opening.
